UNITED STATES PATENT OFFICE.

JOHN WILLIAM HENSON, OF NEW YORK, N. Y.

SEALED PACKAGE.

1,016,149.

Specification of Letters Patent. Patented Jan. 30, 1912.

Application filed August 2, 1911. Serial No. 641,887.

To all whom it may concern:

Be it known that I, JOHN WILLIAM HENSON, a citizen of the United States, and a resident of the city of New York, borough 5 of Manhattan, in the county and State of New York, have invented a new and Improved Sealed Package, of which the following is a full, clear, and exact description.

The object of the invention is to provide 10 a new and improved sealed package, more especially designed for containing lace curtains and other articles, and arranged to protect the articles against dust and light while being held in stock and stored on 15 shelves in stores and other places.

For the purpose mentioned, use is made 20 of a series of envelops each adapted to contain a pair of curtains or other article, the envelops being detachably connected with each other at adjacent sides and having closing flaps at the ends, the envelops being adapted to be folded one on top of the other to form a single package.

A practical embodiment of the invention 25 is represented in the accompanying drawings forming a part of this specification, in which similar characters of reference indicate corresponding parts in all the views.

Figure 1 is a perspective view of the 30 sealed package; Fig. 2 is a plan view of the sealed package with the envelops extended for detachment of one or more envelops; Fig. 3 is a cross section of the sealed package with the envelops folded one upon the other; 35 and Fig. 4 is a perspective view of one of the envelops detached and open at one end for removal of the pair of curtains or other articles contained in the envelop.

In a series of envelops A, of paper or 40 other suitable material and of a suitable size for containing each a pair of curtains or other article, each is provided at one end with a closing flap B for closing the envelop after the pair of curtains or other article is 45 placed in the corresponding envelop. In practice, the flaps B are preferably gummed for readily fastening the said flaps in closed position. The envelops A are connected with each other at the sides by strips C, of 50 paper or other suitable material, pasted or glued to the under sides of the envelops, and each strip C is provided with perforations D to permit of conveniently detaching one envelop from the next adjacent one. 55 The strips C permit of folding one envelop on top of the other so as to form a small

package which can be readily placed on a shelf or other support.

The last envelop of the series of envelops A is provided with locking flaps E adapted 60 to be passed over the ends of the folded envelops A onto the upper surface of the uppermost folded envelop A, as plainly indicated in Fig. 1, and the two flaps E have their free ends connected with each other 65 by a suitable fastening device F, such as a cord and buttons. Now when the envelops are folded one upon the other and the flaps E are extended over the folded envelops and connected with each other by the fastening 70 device F, as plainly shown in Fig. 1, then a sealed package is formed which can be conveniently placed on the shelf or other support and removed therefrom whenever a customer desires a pair of curtains or a like 75 article. In this case, the salesman unfastens the flaps E and then extends the envelops A, to tear off the first envelop which contains a pair of curtains or other article desired by the customer. Thus the customer 80 receives a pair of curtains or a like article in a sealed envelop, it being understood that the selection was made from an exhibition sample.

In practice, the envelops A are consecutively numbered, as indicated in Figs. 2 and 4, so that the stock clerk can see at a glance how many pairs of curtains or other articles remain in the package after one or more sales have been made. Each of the envelops 90 is also provided with a legend, indicating the nature of the curtains or other article contained in the envelop; for instance, as shown in Fig. 2, each envelop A is provided at the outer face of the closing flaps E with the 95 legend "Lace curtains. 4956. One Pair. 3 Yards," thus indicating the nature of the curtains corresponding to the exhibition sample from which the sale was made. One of the flaps E is also provided with a legend 100 indicating the nature of the goods and also the number of articles contained in the original package; for instance, as shown in Fig. 1, the legend reads "Lace curtains. Wide. 4956. 6 Pairs. 3 Yards." thus indicating that six pairs of curtains are contained in the original envelop.

By having the curtains in sealed envelops which can be conveniently folded into a small package, it is evident that the curtains 110 are completely dust and light proof, and hence are not liable to be soiled or liable to

fade while being stored on a shelf or other support.

Having thus described my invention, I claim as new and desire to secure by Letters 5 Patent:

A sealed package, comprising a plurality of connected envelops, each complete in itself and having flaps whereby it may be independently sealed, the connections between 10 said envelops being perforated whereby the envelops may be readily detached with their contents, when desired, certain of said envelops having supplementary flaps adapted to embrace and support the series of envelop-

ops in superposed relation, and means to connect the said supplemental flaps around the package, said means being adjustable whereby a tight package may be formed irrespective of the removal of one or more of the envelops.

15

In testimony whereof I have signed my name to this specification in the presence of two subscribing witnesses.
